UNITED STATES PATENT OFFICE

HERBERT FRIEDMAN, OF BROOKLYN, NEW YORK

DESIGN FOR A POCKET TOOL

Application filed February 19, 1930. Serial No. 34,592. Term of patent 3½ years.

To all whom it may concern:

Be it known that I, HERBERT FRIEDMAN, a citizen of the United States, residing at Brooklyn, county of Kings, and State of New York, have invented a new, original, and ornamental Design for a Pocket Tool, of which the following is a specification, reference being had to the accompanying drawing, forming part thereof.

Fig. 1 is a perspective view of the tool; Fig. 2 is a top plan view of the same and Fig. 3 is a bottom plan view of the tool, showing my design.

What I claim is:

The ornamental design for a pocket tool, substantially as shown.

HERBERT FRIEDMAN.
